UNITED STATES PATENT OFFICE.

GEORGE W. REED, OF GREENFIELD, INDIANA.

HYDROCARBON-BURNER.

No. 883,585.

Specification of Letters Patent. Patented March 24, 1908.

Application filed July 11, 1907. Serial No. 383,335.

To all whom it may concern:

Be it known that I, GEORGE W. REED, of Greenfield, County of Hancock, and State of Indiana, have invented a certain new and useful Hydrocarbon-Burner; and I do hereby declare that the following is a full, clear, and exact description thereof, reference being had to the accompanying drawings, in which like letters refer to like parts.

10 The object of this invention is to improve the construction of hydro-carbon burners and heaters so as to cause a complete conversion of the paraffin oil into gas and the complete combustion of the gas.

15 To that end one feature of the invention consists in the means for supplying air to the gas.

Another feature consists in a retort construction for converting oil into gas.

20 Still a third feature consists in the combination with a stove, wherein the burner is placed within the furnace chamber of the stove, resting upon the bottom if desired and with an air conduit leading from the outside 25 and with the oil conduit entering from the air conduit.

The full nature of this invention will be understood from the accompanying drawings and the following description and claims:

30 In the drawings Fig. 1 is a central vertical longitudinal section through the burner and stove, the oil tank being shown in side elevation and the connecting pipe being centrally broken away. Fig. 2 is a bottom 35 view of the outer section of the air pipe. Fig. 3 is a bottom view of the inner section thereof. Fig. 4 is a horizontal section through the burner on the line 4-4 of Fig. 1.

The furnace chamber 10 of a cooking or 40 heating stove of the like has a bottom 11, the end 12, which may consist of a door, the top 13 which may have a stove lid 14 if desired. An oil supply tank 15 may be located at any 45 suitable point and a pipe 16 leading therefrom to the inlet pipe 17, and this oil conduit being controlled by the valve 18.

Within the furnace chamber of the stove, and upon the bottom if desired, a retort 20 is provided that is preferably made of one casting or piece, cylindrical in form and having a retort chamber 21 with an inlet port 22 and an outlet port 23. A threaded pipe 24 leads from the oil inlet pipe 17 to the retort with its passage way connecting with the port 22. 50 Also a threaded pipe 25 leads from the port 23 upward and parallel with the pipe 24, to a

horizontal portion 25 to which the nozzle 26 is secured which has a downwardly opening outlet port 27 for the gas. This port 27 is preferably located over the center of the 60 retort 20. Said retort has a depression in its upper surface to form a pan or receptacle 28 to receive oil to ignite for starting the device.

In the side wall 12 of the furnace chamber an opening is made through which the section 30 of the air conduit extends, it being located so that its outer end will open into the outer air, whereby air from the outside may reach the interior of the burner. The portion 30 is a tube open at both ends and cut away at 31 horizontally throughout the major portion of its length, as shown in Figs. 1 and 3. It has holes 32 through which the pipes 24 and 25 extend and the pipe section 30 is secured rigidly in place by the nuts 33 on the pipes 24 and 25 that tighten the air pipe section 30 in place against the pipe section 35 and beads 34, as shown in Fig. 1. Therefore, this cut away section 30 is relatively stationary and fixed in position. 70 The other portion 35 of the air chamber is cylindrical, closed at one end and open at the other end so that it will slip longitudinally over and fit tightly upon the portion 30 of the air conduit or chamber. The portion 80 35 is longitudinally slotted at 36, as in Fig. 2, to enable said portion 35 to be slipped readily into place under the beads 34 on the pipes 24 and 25. Thus it is seen that the section 35 may be readily removed by loosening the nuts 33. The slot 36 is provided with an enlargement at 37 which registers with the large hole 38 in the portion 30. When the sections are in place they register with the gas outlet 27, so that the air and 90 gas are forced downwardly through the opening 38.

In operation the valve 18 is first opened and the oil which flows down fills the depression in the retort 20. This oil is ignited and the heat therefrom heats the retort and the pipes 24 and 25 until the heat is sufficient to convert the oil therein into gas. The gas then discharges downwardly through the port 27 and at the issue from said port mixes 100 with the air in the air chamber formed by the pipe sections 34 and 35. This air comes from outside the furnace chamber. The mixed air and gas under combustion makes a downwardly extending flame that is directed with considerable force upon the top 105 of the retort, whereby the heat of the retort 110

is maintained at a high temperature and the oil in passing through the pipe 24 and retort 20 and pipe 25 becomes completely and thoroughly converted into gas. The air chamber is relatively large enough to supply sufficient air to bring about complete combustion of the gas, immediately after it issues downward through the hole 38 leading from the air mixing chamber. The flame being considerable in volume and striking the top of the retort with considerable force, spreads outward and turns upward so that it directly engages and heats the pipe sections 30 and 35 forming the mixing chamber whereby the air is well heated when it comes in contact with the gas issuing from the port 27. The rapid passage of the gas from said port through the hole 38 creates a strong suction which draws the air with it from the air chamber and from the outside.

From the foregoing it is seen that this burner is peculiarly adapted for the complete conversion of the oil into gas and complete combustion of the gas: therefore, the generation of a powerful heat. The burner is chiefly confined within the furnace chamber of the stove so that it is out of the way and all fumes pass out of the stove. While this is an intense heater, at the same time the oil supply pipe extends centrally through the inlet opening of the air conduit or chamber so that the oil in the supply pipe is kept cool until it enters the downward tube 24 in the burner.

What I claim as my invention and desire to secure by Letters Patent is:

1. A hydro-carbon burner including a retort at the lower part thereof, a vertical hydro-carbon supply pipe leading thereto, a vertical pipe leading therefrom, a nozzle arranged to discharge the gas from said last mentioned pipe downwardly towards the retort, and an air chamber on the upper end of said pipes extending over said retort and sur-

rounding the nozzle with an opening under 45 and registering with the port from the nozzle.

2. A hydro-carbon burner including a retort at the lower part thereof, a vertical hydro-carbon supply pipe leading thereto, a vertical pipe leading therefrom, a nozzle arranged to discharge the gas from said last mentioned pipe that discharges the gas 50 downwardly towards the retort, an air chamber on the upper end of said pipes extending over said retort and surrounding the nozzle 55 with an opening under and registering with the port from the nozzle, and a pipe extending into said air chamber and connecting with said hydro-carbon supply pipe, substantially as set forth.

3. A hydro-carbon burner including a retort at the lower part thereof, a vertical hydro-carbon supply pipe leading thereto, a vertical pipe leading therefrom, a nozzle arranged to discharge the gas from said last mentioned pipe that discharges the gas 60 downwardly towards the retort, a horizontal pipe leading to said hydro-carbon supply pipe, and an air chamber formed of two portions of tubing, one portion surrounding said 65 pipe leading to the hydro-carbon supply pipe with the other end open and the major portion thereof cut away on the upper side and with the lower side secured to said pipes leading to and from the retort and the other portion being closed and at one end open so as to 70 slip over said first portion and slotted on the under side to enable it to be put in place or removed, and means for securing said air chamber portions to the pipes leading to and 75 from the retort.

In witness whereof, I have hereunto affixed my signature in the presence of the witnesses herein named.

GEORGE W. REED.
